UNITED STATES PATENT OFFICE.

THOMAS G. BOONE, OF BROOKLYN, NEW YORK.

IMPROVEMENT IN STEAM-BOILERS.

Specification forming part of Letters Patent No. 12,893, dated May 22, 1855.

To all whom it may concern:

Be it known that I, THOMAS G. BOONE, of Brooklyn, in the county of Kings and State of New York, have invented certain new and useful Improvements in Steam-Boilers; and I do hereby declare that the following is a full, clear, and exact description of the same, reference being had to the accompanying drawings, in which—

Figure 1 is a vertical section of a boiler having my improvements applied, the section being taken transversely to the fire-places. Fig. 2 is another vertical section of the same, taken longitudinally through one of the fire-places. Fig. 3 is a horizontal section of the same, taken a short distance above the grates.

Similar letters of reference indicate corresponding parts in each of the several figures.

This invention consists in a novel arrangement of vertical water-tubes, fire-surfaces, water-spaces, and non-conducting lining for giving a proper circulation of water, making a safe, economical, and durable boiler.

To enable those skilled in the art to make and use my invention, I will proceed to describe its construction and operation.

C represents the lower, and D the upper, chamber of the boiler, C being made cylindrical and D slightly conical, as either of those forms is well adapted for strength. Square or other forms may, however, be used if in any instance it may be thought desirable.

E is the lower tube-sheet, which forms the top of the lower water-chamber, and F is the upper tube-sheet, which forms the bottom of the upper water-chamber.

G G G' G'' are five rows of tubes of any length that may be considered most suitable, having their ends fitted in the most approved manner into the tube-sheets E and F and forming communications between the upper and lower water-chambers. The tubes of each row are nearly close together, and the number shown form four fire-chambers H H H H, to which the tubes form side walls or partitions.

I I are two rows of return or descending tubes, also forming communications between the lower and upper water-chambers. These are sheltered from the action of the fire by the rows G' G'', outside which they are placed, and are further protected by being packed around so as to fill the spaces between them with fire-clay and sand or with any suitable

poor conducting material. They may be carried outside the boiler, instead of inside.

J is the shell which incloses the whole space between the upper and lower water-chambers. It is intended to be lined all round with fire-brick or masonry.

K K K K are the fire-grates, of which there is one in each fire-chamber.

H R R are the fire-doors.

V V are shields formed of metal plates or collars of any suitable form to protect the lower part of the tubes G G G' G'', which are exposed to the cooling action of the atmospheric air as it enters the ash-pit. The interstices around the tubes G G G' G'' below the grates may be partially filled with non-conducting substance with or without apertures for the admission of air and passing it in a heated state to aid the combustion of gases above the solid fuel in the fire-chambers.

L L are flues leading from the back part of the fire-chambers through the tube-sheet F and bent to run horizontally through the chamber D below the water-line. These flues may all discharge into a smoke-box or uptake in front or at the side of the boiler, or may have upright tubes p p leading from them through the top of the boiler, as shown, in which case they terminate in the front or side of the boiler and are intended to be furnished with movable stoppers, which can be taken out to clean them. The upright tubes serve as stays to the top of the boiler. Additional stays N N are also provided.

P P are upright plates placed between the upper mouths of the tubes G' G'' and I I for the purpose of keeping a solid body of water over each set of descending tubes I undisturbed by the ebullition.

Q Q are spray-arresters for the purpose of keeping the steam free from water.

Y is the steam-pipe.

When the fire is ignited on the grates K K K K, the radiant heat of the ignited fuel is conducted to the water through the tubes G G G' G'', while that portion of heat not so taken off either remains to support combustion or is carried and applied to the upper part of the tubes and to the tube-sheet F. The upper parts of the tubes are well adapted from the extensive surface therein presented to take from the flame or ignited gases and heated air and make effective in generating

steam the heat of that part of the combustion in addition to that taken direct from the fuel itself through the lower part of the tubes. The heated air and gases are made still further effective by the employment of the tubes $L L$ and $p p$, which present a considerable immersed surface. The ascent of steam and water in the tubes $G G G' G''$ causes a downward current in I to supply the displacement from the chamber C , which after ebullition commences is soon heated by water from the lower end of the tubes $I I$. By this arrangement the tubes $G G G' G''$ are plen-

tifully supplied with water while exposed to the most intense action of the heat radiated by the fuel.

What I claim as my invention, and desire to secure by Letters Patent, is—

The arrangement of the vertical water-tubes, fire-surfaces, upper and lower water-spaces, and non-conducting lining for giving circulation, substantially as herein set forth.

THOMAS G. BOONE.
